BALANCED TO UNBALANCED CIRCUIT CONNECTOR

Harold A. Wheeler, Great Neck, N. Y., assignor,
by mesne assignments, to Hazeltine Research,
Inc., Chicago, Ill., a corporation of Illinois

Application June 5, 1945, Serial No. 597,655

15 Claims. (Cl. 178—44)

1
This invention concerns balanced-to-unbalanced circuit connectors and is particularly directed to such connectors adapted for operation over a wide range of wave lengths.

Balanced-to-unbalanced connectors as such are known in the art. One prior arrangement, which has a simplified construction and may be readily produced, is formed from a conventional coaxial transmission line. It has been the practice in fabricating such a connector to select a coaxial line having a characteristic impedance that is approximately equal to the terminal impedance of the unbalanced circuit to be connected therethrough to a balanced circuit. A pair of thin longitudinal slots are cut into one end of the outer conductor or shield of the coaxial line so that the shield at the slotted end comprises a pair of conductive portions. Usually, the slot length is such that the pair of conductive portions individually have an electrical length equal to one-quarter of the mean operating wave length of the connector. The inner conductor of the coaxial line is bonded at the end to one of the conductive portions provided in the slotted section of the shield. With this construction, one end of the connector may be utilized as a conventional unbalanced transmission line adapted for direct connection with the unbalanced circuit. At the other end of the connector, the two conductive portions of the shield may be utilized as balanced terminals for connection with the balanced circuit.

The described connector is desirable from a mechanical standpoint in view of its simplicity but it has certain electrical characteristics which may be undesirable in particular installations. It has been discovered experimentally that the expedient of slotting the shield conductor and bonding the inner conductor to one of the resulting shield portions causes the characteristic impedance of the balanced circuit provided at one end of the connector to be twice that of the unbalanced circuit provided at the opposite end. In other words, an impedance discontinuity is encountered at the junction of the balanced and unbalanced circuit portions of the connector. Since reflections arise at points of impedance discontinuity, the prior-art connector is unsuited for certain installations.

It is an object of the present invention, therefore, to provide a balanced-to-unbalanced circuit connector which substantially avoids the aforementioned limitation of prior connectors.

It is another object of the invention, to provide an improved balanced-to-unbalanced circuit con-

2
nector having a substantially uniform characteristic impedance throughout its balanced and unbalanced circuit portions.

It is a specific object of the invention to provide an improved balanced-to-unbalanced circuit connector of the coaxial type for operation over a wide range of wave lengths.

A balanced-to-unbalanced circuit connector in accordance with the present invention comprises an outer conductor including a first section and a contiguous second section. The second section has a pair of longitudinal slots extending from one end of the outer conductor and forming in the second section a pair of conductive portions. The connector also has an inner conductor including a first section and a contiguous second section coaxially supported within the first and second sections, respectively, of the outer conductor. The inner conductor is connected to one of the conductive portions formed in the outer conductor substantially at the free end thereof. The first sections of the inner and outer conductors have a relative spacing selected to provide an unbalanced transmission line having a predetermined characteristic impedance at a given operating wave length. The second sections of the inner and outer conductors have a relative spacing selected so that the second section of the inner conductor and the other one of the pair of conductive portions provide a balanced transmission line having approximately the aforesaid predetermined characteristic impedance.

For a better understanding of the present invention, together with other and further objects thereof, reference is had to the following description taken in connection with the accompanying drawings, and its scope will be pointed out in the appended claims.

In the drawings, Fig. 1 is a view, partially in cross section, showing a circuit connector in accordance with the present invention connecting an antenna system to a wave-signal generator; Fig. 2 is an end view of the balanced circuit portion of the connector; Fig. 3 is a schematic circuit diagram of the Fig. 1 connector; Figs. 3a-3d, inclusive, are used in assimilating the individual circuit portions of Fig. 3 with the mechanical connector arrangement of Fig. 1; Fig. 4 is an end view of the balanced-circuit portion of a modified connector of the type of Fig. 1; Fig. 5 is a similar end view of a further modification of the Fig. 1 arrangement; Fig. 6 represents another embodiment of the invention; Fig. 7 is an end view of the balanced-circuit portion of the Fig. 6 con-

necter; and Fig. 8 is a view used in explaining the circuit portions of the Fig. 6 arrangement.

Referring now more particularly to Fig. 1, there is represented a balanced-to-unbalanced circuit connector in accordance with the invention utilized for coupling a wave-signal generator to an antenna system and adapted for operation over a wide range of wave lengths. The connector is generally similar to the well-known coaxial cable in that it comprises an outer cylindrical conductor and a coaxially aligned inner cylindrical conductor, each preferably being circular in cross section. Each conductor includes a first section and a contiguous second section, the first sections being only partially shown and the second sections having a length designated by dimension line L. More particularly, the outer conductor has a grounded first section 10 which may have any length desired in accordance with the intended use of the connector. For this reason only a portion of this section is illustrated. The second section of the outer conductor is designated 11a, 11b and, in a preferred embodiment of the invention, has a length L approximately equal to one-quarter of the mean operating wave length of the connector. This second section of the outer conductor, as shown in Fig. 2, has a pair of diametrically opposed, thin longitudinal slots 14 and 15 extending throughout the entire length of the second section. These slots form in the second section of the outer conductor the pair of conductive portions 11a and 11b, which may individually have an electrical length equal to one-quarter of the mean operating wave length.

The first and second sections of the inner conductor are designated 12 and 13, respectively. They are coaxially supported, by means of suitable insulating spacers 16, 16, within the first and second sections, respectively, of the outer conductor. The inner conductor is connected to one of the conductive portions formed in the second section of the outer conductor. For this purpose, the free end of inner-conductor section 13 is supported by a semi-circular conductive member 17 which is soldered, welded, or otherwise conductively connected to and supported by the free end of portion 11b of the outer conductor.

The first sections 10 and 12 of the inner and outer conductors have a relative spacing selected to provide an unbalanced transmission line having a predetermined characteristic impedance at the mean operating wave length. This unbalanced transmission line may be directly connected with a signal-translating arrangement, such as the short-wave signal generator 20 having an unbalanced output circuit. The second sections 11a, 11b and 13 of the inner and outer conductors have a relative spacing selected so that the second section 13 of the inner conductor and conductive portion 11a of the outer conductor provide a balanced transmission line, having approximately the same characteristic impedance at the mean operating wave length as the unbalanced line provided by sections 10 and 12. The balanced transmission line is directly connected with a dipole antenna consisting of a pair of radiating elements 25 and 26, individually having an effective electrical length equal to one-quarter of the mean operating wave length. Radiating element 25 is directly connected with conductive portion 11a of the balanced transmission line, while the alternate radiating element 26 is connected with the remaining conductor 13 of the balanced line.

The electrical circuits represented by the me-

chanical structure of Fig. 1 are illustrated schematically in Fig. 3. Figs. 3a to 3d, inclusive, indicate the conductive elements of the connector which are the counterparts of the conductors of Fig. 3. The directional arrows 3a-3a to 3d-3d denote the circuit portions represented by Figs. 3a-3d and the impedance notations associated with each such figure designate the characteristic impedance of the particular circuit portion.

10 In Fig. 3 conductors 10' and 12' constitute an unbalanced transmission line. As shown in Fig. 3a, this unbalanced-line portion is provided by sections 10 and 12 of the outer and inner conductors, respectively, of the connector. It has a characteristic impedance Z_0 determined by the relative diameters of its coaxial conductors. Assuming the outer conductor of the connector to have a uniform and preselected diameter equal to d_0 , the diameter d_1 of inner-conductor section 12 is selected with reference thereto in order to obtain the desired characteristic impedance Z_0 for the unbalanced-line portion of the connector. This portion extends from the unbalanced input terminals of the connector to which generator 20

25 is connected to the junction of the first and second sections of the inner and outer conductors. The junction is designated by the broken line A—A in Fig. 3.

The balanced transmission-line portion of the connector starts at the junction A—A. It is formed of the conductors 11a' and 13' which, as shown in Fig. 3b, are provided by section 11a of the outer conductor and one-half of inner conductor section 13, where section 13 is bisected by 35 an imaginary plane X—X. The plane X—X bisects the inner and outer conductors of the connector and is normal to the plane of the drawings. The balanced line 11a', 13' has a characteristic impedance Z_1 determined by the relative spacing or diameters of its conductors. The specific conductor spacing and the resulting value of the characteristic impedance is to be particularly described hereinafter.

Electrically, the connector also embodies a pair 45 of stub lines located at the opposite terminal portions of the balanced-line portion 11a', 13'. The first such stub line, coupled to the balanced-line portion at junction A—A, includes conductors 11b' and 13''. As shown in Fig. 3c, these conductors are provided by outer conductor section 11b and one-half of inner conductor section 13. Since member 17 bonds the ends of these conductors together, as indicated at 17', the first stub line 11b', 13'' is a short-circuited line section. It has a characteristic impedance Z_1 which is equal to that of the balanced-line portion 11a', 13' since, in the Fig. 1 arrangement, the conductors of these two line sections are identical in construction and spacing.

60 The second stub line, located at the free end of the balanced-line portion 11a', 13' includes conductors 11a'' and 11b''. As shown in Fig. 3d, these conductors are provided by the conductive portions 11a and 11b formed in the outer conductor by slots 14 and 15. Since the conductive portions 11a and 11b are joined at the closed ends of slots 14 and 15, the second stub line 11a'', 11b'' is also a short-circuited line section. It has a characteristic impedance Z_2 which may be controlled by variations in the width of slots 14 and 15. This impedance Z_2 may be considered as the balanced characteristic impedance of the outer conductor, that is, the impedance of the slots and the outside of the slotted section of the outer conductor. This second stub line represents

a conductive path from the output terminals of the balanced-line portion 11a', 13' on the external periphery of the slotted section of the outer conductor.

In view of the foregoing discussion of the schematic circuit diagram of Fig. 3, the relationships necessary to establish a uniform characteristic impedance between the balanced and unbalanced-line portions of the connector may readily be determined. It becomes apparent immediately that the impedance Z_1 of the balanced-line portion 11a', 13' must be approximately equal to the characteristic impedance Z_0 of the unbalanced-line portion 10', 12'. This result is obtained by appropriately selecting the diameter d_2 of inner-conductor section 13 with reference to the diameter d_0 of the outer conductor. In the Fig. 1 embodiment the same dielectric material (air) fills the inter-conductor space in the balanced and unbalanced-circuit portions of the connector. For this reason, the balanced and unbalanced-line portions have equal characteristic impedances, as required, by selecting the diameter d_2 of inner-conductor section 13 to be equal to the geometric mean of the diameters d_0 and d_1 of conductor sections 10 and 12, respectively. By thus selecting the spacing of the first sections of the inner and outer conductors as well as the spacing of the second sections of these conductors, the balanced and unbalanced-line portions of the connector represent a uniform characteristic impedance. Where this impedance equals the unbalanced terminal impedance of generator 20 and the balanced terminal impedance of dipole antenna 25, 26, maximum power transfer between the generator and the antenna results. Before considering the wide-band operating characteristics of the connector of Fig. 1, it is expedient to view the impedance relationships of its balanced and unbalanced-line portions from a slightly different viewpoint.

It has been stated with reference to Figs. 3 and 3a that the unbalanced-line portion 10', 12' has a characteristic impedance Z_0 and is provided by conductor sections 10 and 12. Since section 10 is grounded and constitutes a sheath enclosing section 12, the unbalanced-line portion may be viewed as comprising a pair of unbalanced lines connected in parallel and individually having a characteristic impedance equal to $2Z_0$. One of this pair of lines consists of one-half of each of conductor sections 10 and 12, while the other is provided by the remaining halves of these sections, and the imaginary plane X—X designates the meeting plane of the two lines. Therefore, if the contiguous second sections of the inner and outer conductors which provide the balanced-line portion 11a', 13' of the connector have the same diameters and dielectric loading as their first sections, an impedance discontinuity is caused at the junction A—A. The discontinuity arises because the balanced-line portion 11a', 13', assuming the inner and outer conductors of the connector to have uniform diameters and dielectric loading, is formed of conductors having the same spacing as the conductors of each of the pair of parallel-connected unbalanced lines effectively included in unbalanced portion 10', 12' and consequently its characteristic impedance Z_1 is equal to $2Z_0$. In other words, where the inner and outer conductors of the connector have uniform diameters and a homogeneous dielectric therebetween, such as air, the unbalanced-line portion 10', 12' has an impedance Z_0 and the balanced-line portion 11a', 13' has an imped-

ance of twice that value. This discontinuity is encountered in the prior connectors referred to above but is avoided in the Fig. 1 embodiment by enlarging the diameter of inner conductor 13.

5 The change in diameter is selected so that the characteristic impedance Z_1 of the balanced-line portion is approximately equal to that of the unbalanced-line portion.

10 For optimum operation over a wide range of wave lengths, the matched impedance relation between the balanced and unbalanced-line portions of the connector is established at the mean operating wave length. Also, the slots 14 and 15 have a length L equal to one-quarter of the mean wave length. Where these conditions are satisfied, each of the stub lines 11b', 13'' and 11a'', 11b'' represents a short-circuited quarter-wave line. At the mean operating wave length each line is then equivalent to an infinite impedance or an open circuit. The first stub line 11b', 13'' has the same characteristic impedance Z_1 as the balanced-line portion 11a', 13'. For optimum wide-band operation, the second stub line 11a'', 11b'' should have an equal characteristic impedance. This is obtained by appropriately selecting the width of slots 14 and 15. With quarter-wave short-circuited stub lines individually having a characteristic impedance substantially equal to that of the balanced-line portion of the connector, optimum wide-band operation results since the impedance variations of the stub lines cancel one another at the operating wave lengths of the desired range.

35 In certain applications, the connector may be constructed to compensate for impedance variations of the balanced-circuit arrangement coupled thereto. Consider, for example, the case in which the balanced dipole antenna 25, 26 is series-resonant at the mean wave length of the operating band. The impedance of the antenna is, therefore, a minimum at the mean wave length and increases with wave length variations in either direction therefrom. To compensate for such impedance variations of the antenna, loading means may be provided adjacent to the conductive portions 11a and 11b of the outer conductor for appropriately determining the characteristic impedance Z_2 of the second stub line. Such a modification of the connector is represented in Fig. 4 which is an end view of the balanced-line portion. As illustrated, horizontally disposed flange members 21, 21 extend from and along the length of conductive portion 11a. Similar flange members 22, 22 extend along conductive portion 11b. These flanges increase the distributed capacitance between portions 11a, 11b and decrease the inductance thereof to decrease the characteristic impedance Z_2 of the second stub line. As a consequence, the characteristic impedances of the first and second stub lines are different, the impedance of the second line being selected to compensate for impedance variations of the first stub line as well as the dipole antenna 25, 26. More specifically, the characteristic impedance of the second stub line 11a'', 11b'' is less than that of the first stub line 11b', 13' by an amount effective to provide the desired impedance compensation.

70 In Fig. 5 there is represented an end view of the balanced-line section of a further modification of the Fig. 1 connector. The Fig. 5 embodiment is generally similar to that of Fig. 4, differing only in the manner of loading the second stub line for improved wide-band operation in view of a particular balanced-circuit arrangement

coupled with the connector. In the instant case the characteristic impedance of the second stub line $11a''$, $11b''$ is decreased by a first conductive element 23 extending along the length of conductive portion $11a$ and curved around the alternate portion $11b$. A similar conductive element 24 projects from portion $11b$ and extends around portion $11a$. Elements 23 and 24 are proportioned to determine the characteristic impedance of the second stub line as required to effect the desired impedance compensation.

In the embodiments of Figs. 4 and 5 where the second stub line is constructed to compensate for impedance variations introduced by the balanced-circuit arrangement coupled to the connector, consideration was given to the case in which the balanced circuit is series-resonant at the mean operating wave length. For the alternate type of balanced circuit which is parallel-resonant at the mean wave length, a like impedance compensation may be achieved by constructing or loading the second stub line $11a''$, $11b''$ to have a characteristic impedance which is greater than that of the first stub line $11b'$, $13'$.

For some purposes, it may be desired to arrange the connector so that its first stub line $11b'$, $13'$ has a high characteristic impedance. Such a construction is represented in Figs. 6 and 7. The connector is generally similar to that of Fig. 1 and corresponding components thereof are identified by like reference characters. In this embodiment, the second section 13 of the inner conductor has a hollow semi-circular cross section. The schematic circuit diagram of Fig. 3 also represents the electrical circuits included in the connector of Figs. 6 and 7. Likewise, the views of Figs. 3a, 3b and 3d and the impedance notations associated therewith illustrate the counterparts of the electrical portions of Fig. 3 found in the mechanical construction of Fig. 6. The first stub line $11b'$, $13'$ of Fig. 3 is provided by the conductive portion $11b$ of the outer conductor and inner-conductor section 13 as shown in Fig. 8. These conductors have an impedance Z_3 , determined by their relative spacing, which is substantially greater than that of the balanced-line portion $11a'$, $13'$.

In describing the illustrated circuit connectors, the diameters of the first and second sections of the inner and outer conductors have been said to be proportioned so that the balanced and unbalanced-line portions of the connector have substantially the same characteristic impedance. It will be understood that the relative diameters of the conductor sections establish the inter-conductor spacing and the impedance of the transmission lines. The spacing is always selected in view of the dielectric as well as the magnetic properties of the inter-conductor space and the region immediately outside the outer conductor. Where the coaxial conductors have an air separation, the spacing has a given value in order to obtain a desired impedance level. If some other substance having different dielectric and magnetic properties fills the space between the conductors, the spacing usually has a different value to establish the same impedance level for the line. The term "relative spacing" and similar expressions of the appended claims designate the conductor spacing in view of the line dielectric and similar factors. The balanced-line portion of the circuit connector may, if desired, have a different material in the inter-conductor space than the unbalanced-line section. Where the materials filling the inter-conductor spaces of the balanced and unbal-

anced-circuit portions have the proper relative dielectric and magnetic characteristics, each of the inner and outer conductors of the connector may have a uniform diameter while obtaining the desired impedance relationships.

Slots 14 and 15 of the outer conductor are usually thin. That is, the slot width in practical cases is less than the radial clearance between the inner and outer conductors of the connectors.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A balanced-to-unbalanced circuit connector comprising, an outer conductor including a first section and a contiguous second section having a pair of longitudinal slots extending from one end of said outer conductor and forming in said second section a pair of conductive portions, an inner conductor including a first section and a contiguous second section coaxially supported within said first and second sections respectively of said outer conductor and connected to one of said conductive portions substantially at the free end thereof, said first sections of said inner and outer conductors having a relative spacing selected to provide an unbalanced transmission line having a predetermined characteristic impedance at a given operating wave length, and said second sections of said inner and outer conductors having a relative spacing selected so that said second section of said inner conductor and the other one of said pair of conductive portions provide a balanced transmission line having approximately said predetermined characteristic impedance.

2. A balanced-to-unbalanced circuit connector comprising, an outer conductor including a first section and a contiguous second section of a predetermined length having a pair of longitudinal slots extending from one end of said outer conductor and forming in said second section a pair of conductive portions, an inner conductor including a first section and a contiguous second section of said predetermined length coaxially supported within said first and second sections respectively of said outer conductor and connected to the free end of one of said conductive portions, said first sections of said inner and outer conductors having a relative spacing selected to provide an unbalanced transmission line having a predetermined characteristic impedance at a given operating wave length, and said second sections of said inner and outer conductors having a relative spacing selected so that said second section of said inner conductor and the other one of said pair of conductive portions provide a balanced transmission line having approximately said predetermined characteristic impedance.

3. A balanced-to-unbalanced circuit connector comprising, an outer cylindrical conductor including a first section and a contiguous second section having a pair of longitudinal slots extending from one end of said outer conductor and forming in said second section a pair of conductive portions, an inner cylindrical conductor including a first section and a contiguous second section coaxially supported within said first and second sections respectively of said outer conductor and connect-

ed to one of said conductive portions substantially at the free end thereof, said first sections of said inner and outer conductors having relative diameters selected to provide an unbalanced transmission line having a predetermined characteristic impedance at a given operating wave length, and said second sections of said inner and outer conductors having relative diameters selected so that said second section of said inner conductor and the other one of said pair of conductive portions provide a balanced transmission line having approximately said predetermined characteristic impedance.

4. A balanced-to-unbalanced circuit connector comprising, an outer cylindrical conductor of substantially uniform diameter including a first section and a contiguous second section having a pair of longitudinal slots extending from one end of said outer conductor and forming in said second section a pair of conductive portions, an inner cylindrical conductor including a first section and a contiguous second section coaxially supported within said first and second sections respectively of said outer conductor and connected to one of said conductive portions substantially at the free end thereof, said first section of said inner conductor having a diameter selected with reference to the diameter of said outer conductor so that said first sections of said inner and outer conductors provide an unbalanced transmission line having a predetermined characteristic impedance at a given operating wave length, said second section of said inner conductor having a diameter selected with reference to the diameter of said outer conductor so that said second section of said inner conductor and the other one of said pair of conductive portions provide a balanced transmission line having approximately said predetermined characteristic impedance.

5. A balanced-to-unbalanced circuit connector comprising, an outer cylindrical conductor of circular cross section and substantially uniform diameter including a first section and a contiguous second section having a pair of longitudinal slots extending from one end of said outer conductor and forming in said second section a pair of conductive portions, an inner cylindrical conductor of circular cross section including a first section and a contiguous second section coaxially supported within said first and second sections respectively of said outer conductor and separated therefrom by a homogeneous dielectric, means for connecting said inner conductor to one of said conductive portions substantially at the free end thereof, said first section of said inner conductor having a diameter selected with reference to the diameter of said outer conductor so that said first sections of said inner and outer conductors provide an unbalanced transmission line having a predetermined characteristic impedance at a given operating wave length, said second section of said inner conductor having a diameter substantially equal to the geometric mean of the diameters of said first sections of said inner and outer conductors so that said second section of said inner conductor and the other one of said pair of conductive portions provide a balanced transmission line having approximately said predetermined characteristic impedance.

6. A balanced-to-unbalanced circuit connector comprising, an outer cylindrical conductor of circular cross section including a first section and a contiguous second section having a pair of diametrically opposed longitudinal slots extending

from one end of said outer conductor and forming in said second section a pair of conductive portions, an inner cylindrical conductor of circular cross section including a first section and a contiguous second section coaxially supported within said first and second sections respectively of said outer conductor and connected to one of said conductive portions substantially at the free end thereof, said first sections of said inner and outer conductors having relative diameters selected to provide an unbalanced transmission line having a predetermined characteristic impedance at a given operating wave length, and said second sections of said inner and outer conductors having relative diameters selected so that said second section of said inner conductor and the other one of said pair of conductive portions provide a balanced transmission line having approximately said predetermined characteristic impedance.

7. A balanced-to-unbalanced circuit connector comprising, an outer conductor including a first section and a contiguous second section having a pair of longitudinal slots extending from one end of said outer conductor and forming in said second section a pair of conductive portions, an inner conductor including a first section and a contiguous second section coaxially supported within said first and second sections respectively of said outer conductor, conductive means for connecting the free end of said second section of said inner conductor to the corresponding end of one of said conductive portions, said first sections of said inner and outer conductors having a relative spacing selected to provide an unbalanced transmission line having a predetermined characteristic impedance at a given operating wave length, and said second sections of said inner and outer conductors having a relative spacing selected so that said second section of said inner conductor and the other one of said pair of conductive portions provide a balanced transmission line having approximately said predetermined characteristic impedance.

8. A balanced-to-unbalanced circuit connector comprising, an outer conductor including a first section and a contiguous second section having a pair of longitudinal slots extending from one end of said outer conductor and forming in said second section a pair of conductive portions, and an inner conductor including a first section and a contiguous second section coaxially supported within said first and second sections respectively of said outer conductor, conductive means for supporting and for connecting the free end of said second section of said inner conductor to the corresponding end of one of said conductive portions, said first sections of said inner and outer conductors having a relative spacing selected to provide an unbalanced transmission line having a predetermined characteristic impedance at a given operating wave length, and said second sections of said inner and outer conductors having a relative spacing selected so that said second section of said inner conductor and the other one of said pair of conductive portions provide a balanced transmission line having approximately said predetermined characteristic impedance.

9. A balanced-to-unbalanced circuit connector comprising, an outer conductor including a first section and a contiguous second section having a pair of longitudinal slots extending from one end of said outer conductor and forming in said second section a pair of conductive portions individually having an effective electrical length ap-

proximately equal to one-quarter of a given operating wave length, an inner conductor including a first section and a contiguous second section coaxially supported within said first and second sections respectively of said outer conductor, said second section of said inner conductor having an effective electrical length approximately equal to one-quarter of said wave length and being connected to one of said conductive portions substantially at the free end thereof, said first sections of said inner and outer conductors having a relative spacing selected to provide an unbalanced transmission line having a predetermined characteristic impedance at said wave length, and said second sections of said inner and outer conductors having a relative spacing selected so that said second section of said inner conductor and the other one of said pair of conductive portions provide a balanced transmission line having approximately said predetermined characteristic impedance.

10. A balanced-to-unbalanced circuit connector comprising, an outer conductor including a first section and a contiguous second section having a pair of longitudinal slots extending from one end of said outer conductor and forming in said second section a pair of conductive portions individually having an effective electrical length equal to one-quarter of a given operating wave length, means adjacent to said conductive portions for determining the characteristic impedance therebetween, an inner conductor including a first section and a contiguous second section having an effective electrical length equal to one-quarter of said wave length coaxially supported within said first and second sections respectively of said outer conductor and connected to one of said conductive portions substantially at the free end thereof, said first sections of said inner and outer conductors having a relative spacing selected to provide an unbalanced transmission line having a predetermined characteristic impedance at said wave length, and said second sections of said inner and outer conductors having a relative spacing selected so that said second section of said inner conductor and the other one of said pair of conductive portions provide a balanced transmission line having approximately said predetermined characteristic impedance.

11. A balanced-to-unbalanced circuit connector comprising, an outer conductor including a first section and a contiguous second section having a pair of longitudinal slots extending from one end of said outer conductor and forming in said second section a pair of conductive portions individually having an effective electrical length equal to one-quarter of a given operating wave length, flange members extending from said conductive portions along the length of said slots for decreasing the characteristic impedance therebetween, an inner conductor including a first section and a contiguous second section having an effective electrical length equal to one-quarter of said wave length coaxially supported within said first and second sections respectively of said outer conductor and connected to one of said conductive portions substantially at the free end thereof, said first sections of said inner and outer conductors having a relative spacing selected to provide an unbalanced transmission line having a predetermined characteristic impedance at said wave length, and said second sections of said inner and outer conductors having a relative spacing selected so that said second

section of said inner conductor and the other one of said pair of conductive portions provide a balanced transmission line having approximately said predetermined characteristic impedance.

12. A balanced-to-unbalanced circuit connector for operation over a wide range of wave lengths comprising, an outer conductor including a first section and a contiguous second section having a pair of longitudinal slots extending from one end of said outer conductor and forming in said second section a pair of conductive portions individually having an effective electrical length approximately equal to one-quarter of the mean wave length of said range, an inner conductor including a first section and a contiguous second section coaxially supported within said first and second sections respectively of said outer conductor, said second section of said inner conductor having an effective electrical length approximately equal to one-quarter of said mean wave length and being connected to one of said conductive portions substantially at the free end thereof, said first sections of said inner and outer conductors having a relative spacing selected to provide an unbalanced transmission line having a predetermined characteristic impedance at said mean wave length, said second sections of said inner and outer conductors having a relative spacing selected so that said second section of said inner conductor and the other one of said pair of conductive portions provide a balanced transmission line having approximately said predetermined characteristic impedance, and said slots having such width that said conductive portions of said outer conductor provide a stub line having a characteristic impedance substantially equal to that of an additional stub line formed by said second section of said inner conductor and said one conductive portion of said outer conductor.

13. A balanced-to-unbalanced circuit connector for operation over a wide range of wave lengths and for connection with a balanced circuit arrangement which is resonant at the mean wave length of said range comprising, an outer conductor including a first section and a contiguous second section having a pair of longitudinal slots extending from one end of said outer conductor and forming in said second section a pair of conductive portions individually having an effective electrical length approximately equal to one-quarter of the mean wave length of said range, loading means adjacent to said conductive portions for determining the characteristic impedance therebetween, an inner conductor including a first section and a contiguous second section coaxially supported within said first and second sections respectively of said outer conductor, said second section of said inner conductor having an effective electrical length approximately equal to one-quarter of said mean wave length and being connected to one of said conductive portions substantially at the free end thereof, said first sections of said inner and outer conductors having a relative spacing selected to provide an unbalanced transmission line having a predetermined characteristic impedance at said mean wave length, said second sections of said inner and outer conductors having a relative spacing selected so that said second section of said inner conductor and the other one of said pair of conductive portions provide a balanced transmission line having approximately said predetermined characteristic impedance, and said loading means being so se-

lected that said conductive portions of said outer conductor provide a stub line having a characteristic impedance different from that of an additional stub line formed by said second section of said inner conductor and said one conductive portion of said outer conductor and effective substantially to compensate the impedance variations of said balanced circuit arrangement and said additional stub line over said range of wave lengths.

14. A balanced-to-unbalanced circuit connector for operation over a wide range of wave lengths and for connection with a balanced circuit arrangement which is series-resonant at the mean wave length of said range comprising, an outer conductor including a first section and a contiguous second section having a pair of longitudinal slots extending from one end of said outer conductor and forming in said second section a pair of conductive portions individually having an effective electrical length approximately equal to one-quarter of the mean wave length of said range, loading means adjacent to said conductive portions for determining the characteristic impedance therebetween, an inner conductor including a first section and a contiguous second section coaxially supported within said first and second sections respectively of said outer conductor, said second section of said inner conductor having an effective electrical length approximately equal to one-quarter of said mean wave length and being connected to one of said conductive portions substantially at the free end thereof, said first sections of said inner and outer conductors having a relative spacing selected to provide an unbalanced transmission line having a predetermined characteristic impedance at said mean wave length, said second sections of said inner and outer conductors having a relative spacing selected so that said second section of said inner conductor and the other one of said

pair of conductive portions provide a balanced transmission line having approximately said predetermined characteristic impedance, said loading means being so selected that said conductive portions of said outer conductor provide a stub line having a characteristic impedance less than that of an additional stub line formed by said second section of said inner conductor and said one conductive portion of said outer conductor and effective substantially to compensate the impedance variations of said balanced circuit arrangement and said additional stub line over said range of wave lengths.

15. A balanced-to-unbalanced circuit connector comprising, an outer conductor including a first section and a contiguous second section having a pair of longitudinal slots extending from one end of said outer conductor and forming in said second section a pair of conductive portions, an inner conductor including a first section and a contiguous second section coaxially supported within said first and second sections respectively of said outer conductor and connected to one of said conductive portions substantially at the free end thereof, said first sections of said inner and outer conductors having a relative spacing selected to provide an unbalanced transmission line having a predetermined characteristic impedance at a given operating wave length, said second section of said inner conductor and the other one of said pair of conductive portions having a relative spacing selected to provide a balanced transmission line having approximately said predetermined characteristic impedance, and said second section of said inner conductor and said one conductive portion having a relative spacing selected to provide a stub line connected to but having a substantially greater characteristic impedance than said balanced line.
